UNITED STATES PATENT OFFICE.

CHAUNCEY L. C. MAGEE, OF CHICAGO, ILLINOIS.

RADIATOR-HEATER.

1,300,440.

Specification of Letters Patent. Patented Apr. 15, 1919.

Application filed April 25, 1918. Serial No. 230,718.

To all whom it may concern:

Be it known that I, CHAUNCEY L. C. MAGEE, a citizen of the United States of America, and resident of Chicago, county of Cook and State of Illinois, have invented a certain new and useful Improvement in Radiator-Heaters, of which the following is a specification.

This invention relates to electrical devices for heating the water in an automobile radiator to prevent the same from freezing in cold weather.

It will be seen that this is an improvement on the construction shown and described in Patent No. 1,242,711, granted October 9, 1917, for a similar device.

Generally stated, the object of the present invention is to provide an improved construction and arrangement whereby a device of this kind may be attached to the radiator without cutting holes in the latter, and practically without changing the construction of the radiator, and whereby the device itself may be manufactured at a comparatively small cost of production and whereby the device itself, when in use, will be of a more satisfactory character than heretofore.

It is also an object to provide certain details and features of construction and combinations tending to increase the general efficiency and desirability of an automobile radiator electric heating device of this particular character.

To these and other useful ends, the invention consists in matters hereinafter set forth and claimed.

In the accompanying drawings:—

Figure 1 is a front elevation of an automobile radiator showing an electric heating device therefor embodying the principles of the invention.

Fig. 2 is an enlarged vertical section of said heating device.

Fig. 3 is a vertical section on line 3—3 in Fig. 2.

Fig. 4 is a horizontal section on line 4—4 in Fig. 2.

As thus illustrated, the radiator 1 may be of any suitable character, and is provided with the usual or ordinary relief-valve 2 for draining off the contents of the radiator, when such is necessary or desirable. Ordinarily, this valve is secured directly to the radiator. For the purpose of the invention, however, a T-coupling 3 is interposed between said valve and the radiator, and the electric heating device is connected to said T-

through an elbow 4 or any other suitable means.

The said heating device comprises a cylindric casing 5 having a screw-threaded top or cap 6 which is removable therefrom, and which is provided with an internally threaded boss 7 to receive the threaded nipple 8 of the previously mentioned elbow, whereby the heating device is supported in vertical position. In its lower portion, the casing 5 is provided with a shoulder 9, and at its lower end with a central opening 10, the casing being made of sheet metal drawn or spun into the desired shape, although it is obvious, of course, that the cylindric casing or body thus provided can be made in any suitable manner. A sheet metal holder is provided within the casing, said holder having its lower end provided with a shoulder 11 to rest upon the shoulder 9, and this holder having an upwardly extending cylindric wall 12 which is finally bent over at 13 at the top and then brought downward to form the reduced cylindric portion 14 which hangs inside of the top of the holder. This portion 14 has a central opening 15, and a vertically disposed bolt 16 has its head 17 disposed in the recess or well 18 formed by the portion 14, and the lower end of the bolt extends through the opening 10 and is provided with a nut 19 which bears against the bottom 20 of the casing, whereby the shoulder 11 is pulled downward against the shoulder 19 to form a water-tight joint, it being understood that the water from the radiator enters through the coupling 3 and the elbow 4 into the space 21 which surrounds the sheet metal holder, and into the well 18, whereby the water will be heated. The heating element 22 is preferably a coil disposed between cylindric walls 23 of mica or other suitable insulation, whereby the sheet metal holder which has the walls 12 and 14 will be heated in the desired manner. A metal terminal strip or bracket 24 is hung on the lower end of the bolt 16, and the two binding-posts 25 are connected with the terminals of the coil or heating element 22, whereby the electric current will traverse said heating element to produce the desired result. The lower ends of the binding-posts 25 can be connected with a cord in any suitable or desired manner. A sheet metal retainer 26 is inserted inside of the inner mica cylinder 23, this retainer being of any suitable metal and provided with punched out lugs 27 behind which a curved plate 28 is inserted to

C. L. C. MAGEE,
RADIATOR HEATER.
